No. 874,719.

PATENTED DEC. 24, 1907.

G. WOOD.
FORCE FEED OILER.
APPLICATION FILED MAR. 5, 1907.

UNITED STATES PATENT OFFICE.

GEORGE WOOD, OF NEWARK, NEW JERSEY.

FORCE-FEED OILER.

No. 874,719.

Specification of Letters Patent.

Patented Dec. 24, 1907.

Application filed March 5, 1907. Serial No. 360,730.

To all whom it may concern:

Be it known that I, GEORGE WOOD, a citizen of the United States, residing at Newark, in the county of Essex and State of New Jersey, have invented certain new and useful Improvements in Force-Feed Oilers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to a lubricator, and is of the class known as "force feed oilers," and is designed for use particularly on the motors of auto-vehicles, motor boats, and all gas motors, and for lubrication of every description where force is used, transmitted from the mechanism being driven, to feed oil to the wearing parts.

The invention is designed to provide an oiler, of this kind, that is very cheap to make, and its simplicity insures its constant operation.

The oiler also embodies a construction that can be installed on any part of the machine, and has various means for adapting itself to being driven from either side or end of its casing.

The invention also provides an oiler, of this kind, that if it should be accidentally driven backward, will not tend to break or destroy any of the parts, as there is provision made for taking up any motion in reverse direction and relieving the pumps of any strain.

The invention is illustrated in the accompanying drawing, in which

Figure 1 is a plan view of the oiler with the cover removed. Fig. 2 is a section on line 2, 2, in Fig. 1. Fig. 3 is a view similar to Fig. 2, but showing only a portion of the device, and illustrating the pump in the position where it is about to force some oil from the oiler. Fig. 4 is a detail section of the connection between the oil tube, leading to the element to be lubricated, and a connection with the casing of the oiler.

In the drawings the casing 10 is provided with bearings 12 in which is arranged a shaft 11. On either side of the shaft 11 can be placed a pulley 13 that is adapted to receive motion, by means of a belt or other transmitting medium, from some moving part of

the machine, and in this way a worm-wheel 14 is caused to operate, at a slower speed, a gear wheel 15 which is mounted on a shaft 16. This shaft 16 rotates in the standards 17 60 which are slotted at the top, and receive blocks 18 bearing on the top of the shaft 16. Spring keys 19 pass through the elements to hold the blocks 18 down fast on the shaft 16. It is thus seen that this shaft 16 has a slow 65 steady rotary motion, and it thus carries around with it studs 20, the function of these studs being described hereinafter.

Parallel to the shaft 16 is a rod 21 which is mounted in the standards 22, secured to the bottom of the casing, and this rod 21 is provided with levers 23 on top of one end of each of which is placed the plate 24, made of hard steel, to take up the wear from the studs 20 which engage them, and on the other ends 70 of the levers 23 is the forked portion 25, each of the forked ends 25 of the levers 23 engaging a collar 27 fastened to the piston 26. The piston 26 is forced downward by means of a spring 28, between the collar 27 and a 80 web 29 in the casing, and a second spring 30, arranged below the forked end 25 of the lever 23, around each piston 26, engages the top edge of a tubular portion 31, which portion is an enlargement of the casting of which the 85 casing is made, although this preferred form might be departed from, and the tubular portion 31, forming the pump casing, might be attached to the casing and made of a separate piece of material. As the shaft 16 revolves, the studs 20 engage the plate 24 of each lever 23 and press down one end, as shown in Fig. 3. This pushes the piston 26, of each pump, upward against the action of the spring 28, and the lower end of the piston 95 uncovers a perforation 32 which forms an inlet to the pump from the casing, and a small quantity of oil is thus drawn into the bore in which the piston 26 operates. As each stud 20 passes over the edge of the plate 24 of each lever 23, the spring 28 snaps the piston in each pump sharply downward, and a small quantity of oil is thus forced from the casing down into an oil tube to be described hereinafter.

The action of the spring is so swift and sharp that the oil is forced down from the casing in a positive manner, and the feeding of the oil is assured. Instead of all the studs 20 being arranged in line, as shown in Fig. 1, 110 they might be staggered circumferentially so that the pumps will be successively operated,

as will be understood. If by chance the oiler should be run in a reverse direction, the studs 20 will engage the under side of one end of each lever 23, and the forked end 25 will be allowed to give by reason of the compression of the spring 30, and after the studs 20 have passed beyond the lever 23, the spring 30 will spring the forked end of the lever back into place, and there will be no damage resulting.

10 At the bottom of each pump is screwed a nut 33 having a threaded portion extending therefrom, and in the portion 33 is a screw 34 by means of which the flow of oil through the tube can be increased or diminished. On the threaded extension of the nut 33 is arranged a union 35 which bears up against a conical head 36 having a stem 37, both of these elements being longitudinally bored to furnish a passage for oil, and the conical head 36 is forced up into a recess 38 in the nut 33, and a tight joint is the result. A copper or similar tube 39 can then be passed over the stem 37 and secured thereto, in any well known manner, and each of these tubes 39 can be led off to the point to be lubricated, as is now common in machines of this class. A modified form however can be installed, as shown in Fig. 4, where a tube 40, which can be made of glass or quartz or similar transparent material, fits over the stem 37 and is secured thereto by suitable sealing matter 41, and the oil tube 39 is fitted into the other end of the glass tube, this construction forming a sight glass whereby the 35 end of the stem 37 can be observed to ascertain whether the feeding of oil is really taking place.

The casing is provided with a cover 43 which can be suitably perforated at the top 40 and provided with a swinging lid 42.

One of the principal advantages of this construction of oiler is its extreme simplicity, and this taken in conjunction with its positive action, provides a lubricating mechanism that is very desirable.

Having thus described my invention, what I claim is:—

1. An oiler comprising a casing, a series of pump cylinders in the casing, a reciprocating piston in each pump cylinder and projecting therefrom, a spring encircling each piston and bearing thereon, the other end of the spring bearing on the casing, a lever engaging each piston, and means for individually engaging each lever to compress the spring and then to release the lever to allow the spring to operate the pump.

2. An oiler comprising a casing, a series of pump cylinders in the casing, pistons in the pump cylinder and projecting therefrom, a spring engaging each piston and adapted to operate it, a lever for each piston for compressing the spring, and means for operating and releasing the levers.

3. An oiler comprising a casing, a series of 65 pump cylinders therein, a piston in each pump cylinder and projecting therefrom, a spring on each piston, levers pivoted in the casing, one lever engaging each pump piston, a shaft adapted to rotate in the casing, and 70 studs on the shaft, each stud being arranged with a lever in its path of travel.

4. An oiler comprising a casing, a series of pump cylinders therein, a piston in each pump cylinder, a spring encircling each piston to operate it in one direction, a lever for each piston having a forked end engaging the piston and each lever being pivoted intermediate of its ends, a shaft in the casing, and a stud on the shaft for each lever and arranged 80 to operate the lever to compress its spring.

5. An oiler comprising a casing, a series of pump cylinders therein, a lever engaging each pump cylinder, a spring on each pump, a second spring on each pump to receive the 85 reverse motion of its lever, and means for operating the levers.

6. An oiler comprising a casing, a series of pump cylinders in the casing, a piston in each pump cylinder, a pair of springs on each piston acting against one another to hold the piston in its normal position, and means for forcing each piston against one of its springs and releasing it when compressed.

7. An oiler comprising a casing, a series of 95 pump cylinders in the casing, a piston in each pump cylinder, a pair of springs on each piston acting against one another to hold the piston in its normal position, levers, one for each piston to actuate it, and a shaft having 100 studs thereon to operate the levers.

8. An oiler comprising a casing, a pump cylinder in the casing, a piston in the pump cylinder, a collar on the piston, a web in the casing, a spring between the collar and the 105 web, a second spring between the collar and the pump, a lever having one end to engage the collar, the lever being pivoted intermediate of its ends, a shaft in the casing, a stud on the shaft to engage the free end of the lever to operate it, and means for rotating the shaft.

9. In an oiler, a casing, a pump cylinder therein, a piston in the pump cylinder, a pair of springs on the piston and acting against 115 one another, a lever engaging the piston to operate it in one direction and compress one of the springs, the lever when operated in the other direction being disengaged from the piston and acting to compress the other 120 spring.

In testimony, that I claim the foregoing, I have hereunto set my hand this 4th day of March 1907.

GEORGE WOOD.
